METHOD FOR OBTAINING CHLORINE

William C. Leete, Longmeadow, Mass.

Application November 28, 1939, Serial No. 306,522

5 Claims. (Cl. 204—164)

This invention relates to a method for obtaining chlorine from an aqueous solution of its common salts, such as sodium chloride, calcium chloride, etc.

An object of the invention is to provide a method for this purpose, which may be carried out by the employment of apparatus of simple, relatively cheap, construction, and which may be of portable character so as to be easily transported from place to place for functioning as a chlorinating apparatus. In this manner it may be used for treating contaminated water supplies, flooded areas, washing water for dairies, etc.

The principle underlying the present process is derived from the fact that a solution of chloride salt when suspended in air in a highly divided state, as in a mist, will upon passing through the disruptive spark of a high tension electrical discharge, become decomposed or dissociated for liberating the chlorine therefrom as a gas. The chlorine thus obtained may be used directly for chlorinating purposes or led into containers for storage.

Referring to the drawing, which show a preferred arrangement of the apparatus,

Fig. 1 is a view of the entire apparatus in somewhat diagrammatic form so as to display all parts of the apparatus clearly; and

Fig. 2 is a detailed and somewhat enlarged view, and in section, of the electric discharge device.

Referring to the drawing in detail; 1 indicates a supporting frame upon which all parts of the apparatus may be suitably mounted. On a lower partition 2 of this frame is mounted a power unit which may be an electric motor 3, an air receiver tank 4, and an electrical transformer 5 from which the high tension current is obtained for the electrical discharge device hereinafter described. In the embodiment shown the primary current for the transformer 5 and the current for operating the motor 3, is obtained from any suitable outside source. For situations where such current is not available the apparatus may comprise an internal combustion engine power unit and magneto or other suitable appurtenances for generating the high tension current for the electric discharge device.

Mounted on the upper shelf 6 of the supporting frame is a suitable air compressor 7, atomizing tank 8 closed on all sides except for the pipe connections thereto as shown, and an electric discharge device 9. A belt 10 with pulleys 11 and 12 serve as driving connections between motor 3 and air compressor 7.

An air conducting pipe 13 leads from the air compressor 7 to one end of the air receiver tank 4 as shown. This tank will also be suitably provided with an air pressure indicator thereon as at 14, the pressure therein during operation being normally maintained within the range of 5 to 10 pounds above atmosphere. The atomizing chamber 8 has screwed into its top wall a four-branch pipe-fitting 15 and also screwed into its bottom wall a four-branch pipe-fitting 16. A gauge glass tube 17 is provided to show the level of liquid within the atomizing chamber 8 and the upper branch 18 of said gauge glass tube is connected to the left side of the pipe-fitting 15 and the lower branch 19 of said gauge glass tube is connected to the left side of the pipe-fitting 6. A filling cap 20 is provided on the upper branch 18 whereby liquid may be introduced therethrough and into said atomizing chamber 8.

15 The upper end of the pipe-fitting 15 is closed by a plug 21 through which two holes are bored, one to receive a relatively small diameter air tube 22 and the other to receive a similarly small-sized liquid tube 23, said tubes 22 and 23 being extended down through the pipe-fitting 15 in spaced relation from the sides thereof and joined together in an atomizing nozzle 24 at the lower end thereof. As shown, the atomizing nozzle 24 is positioned in the upper part of the chamber 8 so as to be above the level of liquid contained therein, said level being indicated by dotted line 42. An air conducting pipe 25 leads from one end of the air chamber 4 upwardly for connection with said atomizing air pipe 22. A safety air valve 26 is connected in said pipe 25 and is preferably adjusted to release air therefrom at about fifteen pounds' pressure. The right hand side of the lower pipe-fitting 16 connects with a liquid conducting pipe 27 which leads through a sediment collecting chamber or cleaner 29 and upwardly for connection with the liquid conducting atomizing pipe 23. A drain valve 28 is provided in the lower part of said pipe 27, to drain liquid from the system when desired. The right hand side of the upper pipe-fitting 15 is connected to a mist conducting pipe 30 which leads into the electric discharge device 9.

As shown in Fig. 2, the casing for the electric discharge device 9 has upper and lower vertical openings 31 and 32 and right and left side horizontal openings 33 and 34. In said horizontal openings 33 and 34 are mounted spark plugs 35 and 36, each having a single electrode 37 and 38 respectively which are suitably insulated and spaced apart to provide a spark gap across which

a flaming electrical discharge is created by the high tension current of the transformer 5. The high tension current wires from the transformer 5 to the separated electrodes 37 and 38 are indicated at 42 and 43. A suitable working voltage for said high tension current is 10,000 volts. The upper opening 31 of the casing 9 is closed by a bushing 39 through which extends the aforesaid pipe 30 and the lower end of said pipe 30 is preferably flattened into elongated shape with its longer axis parallel to that of the electrodes 37 and 38. In this manner the mist of salt solution is blown across the disruptive spark of the electrical discharge with a maximum of contact therebetween.

The lower opening 32 of said electrical discharge device 9 is connected with a T-pipe-fitting 40 mounted on the upper shelf 6 of the supporting frame 1. The lower branch of said pipe-fitting 40 serves as collecting chamber for the solid residues which result from said electrical discharge. The chlorine gas which is liberated by the electrical discharge passes out the lateral branch 41 of said pipe-fitting 40, to which may be connected any suitable dispensing hose for leading the chlorine gas to storage containers or for use in chlorinating.

The operation of the apparatus is as follows: There is first introduced through the filling cap 20 and into the atomizing chamber 8 an aqueous solution of the chloride salt (salt water for instance), and the chamber 8 is only partially filled therewith, as indicated by dotted line 42. The transformer 5 is switched on to create an electrical discharge across the electrodes 37 and 38 of said electrical discharge device. The motor 3 having been set in operation, drives the compressor 7 to create pressure of air within the tank 4 and air under pressure is led therefrom up pipe 25 and through the air tube 22 and out the atomizer nozzle 24. This entrance of air under pressure into the atomizer chamber 8 forces liquid solution therefrom out the bottom of the chamber through pipe 27, cleaner 29, and upwardly to the liquid tube 23 for introducing liquid solution to said atomizer nozzle 24 within the upper portion of said chamber 8, this action being completed by the suction effect of air passing through the nozzle 24. The nozzle 24 combines the air in tube 22 with liquid solution coming through tube 23 and atomizes the liquid from the latter into a mist which collects in the upper portion of said chamber 8. This mist is under pressure due to the incoming air from air tube 22 and consequently passes out from the chamber 8, through the space surrounding the pipes 22 and 23 through pipe 30 and down through the electrical discharge device 9. As the mist leaves the end of pipe 30 it is spread out into a wide thin sheet by the flattened end of said pipe and flows through the discharge across said electrodes 37 and 38, the action of which is to decompose the mist and liberate the chlorine therefrom. The liberated chlorine passes

out as a gas mixed with air, through the pipe 41 and the solid products of said decomposition will collect in the bottom of said T-pipe-fitting 40 as above described.

5 The action of the electrical discharge upon said mist not only liberates the chlorine as described but also ozonizes the air in which said mist is suspended, whereby the gas obtained at the outlet 41 will have sterilizing properties of very high degree.

I claim:

1. The method of obtaining chlorine which consists in taking an aqueous solution of a chloride salt, converting the same into a vapor or mist, blowing said vapor or mist in a confined passage through the gap between the spaced terminals of a sparking device while producing a disruptive spark across said terminals from a high tension alternating current supply whereby 20 chlorine gas is separated from said vapor or mist.

2. The method of obtaining chlorine which consists in taking an aqueous solution of a chloride salt, converting the same into a vapor or mist, blowing said vapor or mist in a confined 25 passage through the gap between the spaced terminals of a sparking device while producing a disruptive spark between said terminals from a high tension alternating current supply whereby chlorine gas is separated from said vapor or mist, 30 and conducting said separately recovered chlorine gas away from said confined passage.

3. The method of obtaining chlorine which consists in taking an aqueous solution of a chloride salt, atomizing the same with compressed 35 air into a vapor or mist, discharging said vapor or mist under pressure in a confined passage through the gap between the spaced terminals of a sparking device while producing a disruptive spark across said terminals from a high tension 40 alternating current supply whereby chlorine gas is separated from said vapor or mist.

4. The method of obtaining chlorine which consists in taking an aqueous solution of a chloride salt, atomizing the same with compressed 45 air into a vapor or mist, discharging said vapor or mist under pressure in a confined passage through the gap between the spaced terminals of a sparking device while producing a disruptive spark across said terminals from a high tension 50 alternating current supply whereby chlorine gas is separated from said vapor or mist, and conducting said separately recovered chlorine gas away from said confined passage.

5. The method of obtaining chlorine which 55 consists in taking an aqueous solution of a chloride salt, converting the same into a vapor or mist, blowing said vapor or mist in the form of a thin flat sheet extended across the gap between the spaced terminals of a sparking device while producing a disruptive spark across said terminals from a high tension 60 alternating current supply whereby chlorine gas is separated from said vapor or mist.
